UNITED STATES PATENT OFFICE.

BERTIE E. MILLS, OF CHICAGO, ILLINOIS, ASSIGNOR TO MILLS NOVELTY COMPANY, OF CHICAGO, ILLINOIS, A CORPORATION OF ILLINOIS.

TREMOLO DEVICE FOR ELECTRIC SELF-PLAYING VIOLINS.

1,407,434.

Specification of Letters Patent. Patented Feb. 21, 1922.

Application filed July 11, 1921. Serial No. 483,936.

To all whom it may concern:

Be it known that I, BERTIE E. MILLS, a citizen of the United States, residing at Jackson Boulevard and Green Street, Chicago, in the county of Cook and State of Illinois, have invented a new and useful Improvement in Tremolo Devices for Electric Self-Playing Violins, of which the following is a specification.

10 My invention relates more particularly to an improvement in that feature of the self-playing violin of United States Letters Patent to Henry K. Sandell, No. 855,021, which serves for producing the tremolo or vibrato 15 effect of human violin-playing.

The more important objects of my present improvement are to enhance the sensitivity of the mechanism for the stated purpose and to enable the force of the 20 vibrato effect to be regulated.

Referring to the accompanying drawings, Figure 1 is a broken plan view of an electric self-playing violin of the type exemplified in the aforesaid patent, with my improvement embodied therein and showing enough of the instrument and its operating parts to enable the operation of the improved feature to be readily understood; and Figure 2 is a broken section on line 30 2-2, Fig. 1.

The violin 3 is played by the sounders 4, 4, or bows, on rotary shafts 5, 5, one for each string 6, and driven by an electric motor 7 having its shaft suitably geared to the shafts 5, the gearing being enclosed in a housing 8. The shafts 5 are operated to maintain the sounders normally raised off the strings, by levers 9 connected between their ends with a rock-shaft 10 journaled 40 in suitable bearings, the levers being spaced apart by collars 11 and carrying at their rear ends, armatures 12 provided to be worked by electromagnets 13 for rocking the levers to apply the constantly rotating 45 sounders to the violin-strings while they are being fingered by mechanism, of which a portion is indicated at 14 in Fig. 1, for playing one string.

The tail-piece 15, which is shown in Fig. 50 1 to be connected at its forward end by strings 16, 16 with the bridge 17, is vibrated substantially as and for the purpose explained in the aforesaid patent by my improved mechanism for the purpose, which 55 is described as follows:

The rod 18, connected at one end with the tail-piece, passes at its opposite, threaded end through the upper end of the pendulous lever 19, fulcrumed at 20 and with which the rod is adjustably connected by the 60 thumb-nuts shown thereon to bear against the opposite faces of the lever. The lower part of the pendulous lever is bent into the recess-form shown, and the end below the recess alines with the straight lever-section 65 above the recess and carries adjustably a horizontally extending weight 21 having adjustably fastened on its advance-end a projecting headed push-stem 22. In the lever-recess is provided an armature 23 opposed to the poles of an electromagnet 24 which is suspended on the lower-end portion of a metal plate 25 secured to depend from the portion of the frame 26 on which the lever 19 is fulcrumed, as shown, and through a 70 relatively wide opening 27 in which an opening 27^a in the partition 28 the swinging lever passes. A block 29 of insulating material is secured on the lower part of the plate 25 and has a metallic lever 30 fulcrumed upon it at 30^a between the lever-ends. A spring 31 bears outwardly against the upper part of the lever 30, the lower end of which is opposed to the push-stem 22; and this lever carries on its inner face, 85 at 32, a circuit-closing spring contact. The electromagnet is included in the circuit of an electric generator, conventionally indicated at 33, one side of which is connected by a conducting wire 34 with a binding-post 90 34^a on the lever 30. From the other side of the generator extends the wire 35 to a pivoted switch-lever 36 applicable to either of two contacts 36^a and 36^b and simultaneously to both. A branch 35^a of the circuit connects the contact 36^a with the outer windings α of the spools 24, from which it leads to a binding-post 37; another branch, 35^b connects the contact 36^b with the inner windings γ of the spools (those nearest the 95 magnet-cores) and leads to the same binding-post. A branch 35^a of the circuit connects the contact 36^a with the outer windings α of the spools 24, from which it leads to a binding-post 37; another branch, 35^b connects the contact 36^b with the inner windings γ of the spools (those nearest the 100 magnet-cores) and leads to the same binding-post.

By applying the switch-lever 36 to either contact, the electromagnet is energized comparatively mildly, and more forcibly when 105 applied to the contact 36^b, to attract the armature and swing the lever to impel the tail-piece in one direction, by which movement of the lever the stem 22 pushes against the lever 30 to separate the spring-contact 32 110

from the terminal of the binding-post 37 and break the circuit, thereby deenergizing the electromagnet and compressing the spring 31. With the electromagnet deenergized, the 5 weight 21 swings the lever 19 backward to impel the tail-piece in the opposite direction, whereupon the recoil of the spring 31 turns the lever 30 to apply the contact 32 to the terminal 37 and again energize the electromagnet. These successive movements of the 10 lever 19 are rapidly repeated so long as the switch remains closed at a contact 36^a or 36^b, with the result of shaking the tail-piece with greater or less force, depending on the particular contact engaged by the switch-lever 15 36; and the resultant vibration of the violin-strings varies the pitch of each string being played by a sounder 4 to produce the desired vibrato effect. To enhance to the utmost the 20 force of the vibratory action of the tail-piece, the elongated contact-end of the lever 36 is caused to bridge the contacts 36^a and 36^b, thereby including both the inner and outer electromagnet-windings in the circuit and 25 accordingly increasing the magnetic power.

I realize that considerable variation is possible in the details of the construction of my improved device herein shown, and I do not intend to limit my invention thereto except 30 as pointed out in the appended claims, in which it is my intention to claim all the novelty inherent in my invention as broadly as permissible by the state of the art.

I claim:

35 1. In combination with a stringed instrument, a pendulous vibratory lever connected with the strings of the instrument, and electric means for vibrating said lever, comprising an electromagnet in an electric circuit including a switch having contact-members respectively connected with the inner and outer electromagnet-windings and a lever-member operative to close the circuit at either contact to energize the electromagnet for regulating 40 the force of said lever's vibrations.

2. In combination with the tail-piece of a stringed instrument, a pendulous vibratory weighted lever connected with the tail-piece and carrying an armature, an electromagnet in an electric circuit, and a lever fulcrumed 50 between its ends adjacent the electromagnet, spring-pressed at one side of its fulcrum and carrying an electric contact at the opposite side thereof to engage a terminal in said circuit and extend into the path of the 55 weight on the lever.

3. In combination with the tail-piece of a stringed instrument, a pendulous vibratory bent lever connected with the tail-piece and carrying an armature and a weight having a 60 push-stem adjustably projecting from the weight, an electromagnet in an electric circuit, and a lever fulcrumed between its ends adjacent the electromagnet, spring-pressed at one side of its fulcrum and carrying an 65 electric contact at the opposite side thereof to engage a terminal in said circuit and extending into the path of said push-stem.

4. In combination with the tail-piece of a stringed instrument, a pendulous vibratory weighted lever connected with the tail-piece and carrying an armature, an electromagnet in an electric circuit containing a 70 switch having a pair of contacts for separate and simultaneous engagement by the switch-lever, one of said contacts being included in a branch of the circuit leading through the outer windings of the electromagnet-spools to a binding-post and the other contact being 75 included in another branch of the circuit leading through the inner windings of said spools to said binding-post, and a lever fulcrumed between its ends adjacent the electromagnet, spring-pressed at one side of its fulcrum and carrying an electric contact at the 80 opposite side thereof to engage a terminal on said binding-post and extend into the path of 85 said weight.

BERTIE E. MILLS.
